2 SHEETS—SHEET 2.

UNITED STATES PATENT OFFICE.

EDWIN O. STEINBAUER, OF NILES, MICHIGAN.

PRIMING ATTACHMENT FOR INTERNAL-COMBUSTION ENGINES.

1,340,087.

Specification of Letters Patent. Patented May 11, 1920.

Application filed February 6, 1918. Serial No. 215,602.

To all whom it may concern:

Be it known that I, EDWIN O. STEINBAUER, a citizen of the United States, residing at Niles, in the county of Berrien and 5 State of Michigan, have invented certain new and useful Improvements in Priming Attachments for Internal-Combustion Engines, of which the following is a specification.

10 The present invention has reference to improvements in auxiliary charge forming devices for use in connection with internal combustion engines and it is the dominant object of the invention to provide a priming 15 device which will permit the placing of a highly combustible or explosive charge in the combustion chambers of the cylinders of an engine to which the device is connected, whereby the same can be quickly and effectively started irrespective of the temperature of the engine cylinders or of the atmosphere, thereby effecting a material saving in electricity used for ignition purposes.

Another and equally important object of 20 the invention is to provide the priming device or attachment with a novel form of mixer whereby the proper proportions of air will be mixed with the gaseous fuel to render the same highly combustible previous to its introduction into the engine cylinders.

Other independent objects are to provide features of construction of portions of the attachment which tend toward the attainment 35 of the aims irrespective of the relation in which they are used.

Other objects will be in part obvious and in part pointed out hereinafter.

The invention accordingly consists in the 40 features of construction, combinations of elements and arrangement of parts which will be exemplified in the construction hereinafter set forth, and the scope of the application of which will be indicated in the 45 claim.

In the accompanying drawings, wherein I have shown one of various possible embodiments of my invention:

Figure 1 is a longitudinal section through 50 the hood of a motor driven vehicle having my improved priming attachment connected to the engine or motor thereof,

Fig. 2 is a vertical section through the novel mixer,

55 Fig. 3 is a sectional view on the line 3—3 of Fig. 2 looking in the direction of the

arrow and showing the screen partly broken away,

Fig. 4 is a detail in perspective of the novel form of cut-off means employed for 60 controlling the passage of the priming charge into the engine cylinders,

Fig. 5 is a vertical transverse section through the cut-off means, and

Fig. 6 is a fragmental detail in perspective of the operating means for the priming attachment.

Similar reference characters refer to similar parts throughout the several views of the drawings.

Having more particular reference to the drawings E represents the engine of the motor driven vehicle to which the improved priming attachment is connected and H the hood of said vehicle. The engine E, is of course, provided with the usual intake manifold i, which manifold extends from a suitable charge forming device such as a carburetor or the like to which the gaseous fuel is fed.

Supported at a point in proximity to the upper rear portion of the hood H and attached to the adjacent side of the cowl is an auxiliary fuel tank or reservoir 1, said reservoir having an outlet opening formed in the lower portion thereof with which the intake neck of the mixer designated in its entirety by the numeral 2 is connected, said neck being indicated by the numeral 3. This reservoir has a filling spout 1 of any ordinary well known construction, whereby said reservoir can be readily filled when the occasion requires. In this connection, it is to be noted that the mixer comprises a substantially cup shaped container having the upper portion of the same internally

55 screw threaded as at 4 and adapted to receive a complementally screw threaded portion formed upon the lower end of a cover or cap 5. In this cap 5 there is formed a passage 6, a portion of which is screw threaded and provided with a valve seat 7 whereby a needle valve 8 may be turned into engagement with the same, said needle valve, of course, being provided with the usual type of handle 9 whereby rotation of the same will be facilitated. To insure fluid pipe connection between the valve and the passage 6 of said cap, a stuffing gland 10 of conventional construction may be and

105 preferably is engaged about the outer portion of the valve stem and with the adjacent

portion of the cap, which as will be noted, is screw threaded. Further, a gasket 11 or other similar form of packing means is arranged between the marginal portions of the 5 cup shaped container of the mixer and the cap or cover 5. Arranged in an opening formed in the cap and communicating with the channel 6 is a short conduit or neck 12, which as will be noted, has the lower end of 10 the same extending downwardly into the mixer. An air intake conduit 13 is received in a suitable channel or way formed in the cover 5 and as will be noted, communicates with the interior of the mixer, thereby providing the necessary means for permitting 15 the proper proportions of air to be mixed with the gaseous charge delivered into the mixer by way of the neck 12. To filter this air, a screen or other foraminated element 14 is arranged about the neck 12 and has its marginal portion secured to the adjacent 20 portions of the cap 5.

Connected to the bottom of and communicating with the mixer 2 is a conduit 15, serving 25 as means for conducting the gaseous charge to the engine, said conduit having the other end of the same engaged with a branch conduit 16, the opposite ends of which are connected through the medium of 30 elbows 17 with the intake exhaust manifold *i* of the engine. A rotatable valve or cut-off means 18 is interposed in the conduit 15 and has an arm 19 secured to the rotatable valve element thereof, which arm has 35 its outer end looped as at 20 to receive an eyelet 21 detachably secured to the adjacent end of an operating rod 22, the eyelet, of course, being secured to the looped end 20 of the arm 19 by means of a locking nut or 40 like fastening means. To secure the valve 18 to the engine an arm 18' is engaged at one end with the casing thereof and has the remaining end connected to one of the bolts holding the manifold securing brackets. 45 The remaining end of the rod 22 is looped and pivotally engaged with a crank shaft 23 rotatably mounted in bearings 24 upon the under side of the footboard *b* of the vehicle, said board having an opening 50 formed therein for receiving a foot pedal 25 therethrough, which pedal is pivotally engaged with the remaining end of the crank shaft 23 as clearly shown in the Fig. 6.

To use the improved priming attachment, 55 the needle valve 8 is opened to the desired extent by an operator, thus permitting quantities of combustible fuel to flow from

the tank or reservoir 1 into the mixer 2 whereupon it will be supplied with the proper proportions of air to render the same 60 highly combustible. From here, the charge will be delivered into the conduit 15 and from thence conducted to the intake manifold *i* through the branches 16 and the elbow 17 engaged with the extremities thereof; it of course being understood that the valve means 18 has been previously moved to its open position by depressing the foot pedal 25 and as a consequence, 65 rocking the arm 19 connected to the rotatable valve element. In this way, it will be readily understood that a highly combustible charge will be delivered into the intake manifold *i* and from there, the same will be drawn into the combustion chambers of the 70 engine cylinders. Hence, when the spark or other form of ignition means is applied, the highly combustible charge will be instantly ignited, thereby imparting the initiative working impulse or impulses to the pistons 75 of the engine cylinders. As means for normally returning the valve 18 to its closed position and as a consequence, interrupting communication between the reservoir 1 and the intake manifold *i*, a contractile coiled 80 spring 26 has one end engaged with the arm 19 while the remaining end is engaged with the under side of the footboard *b* as at 27.

Manifestly, the construction shown is capable of considerable modification and such modification as is within the scope of my 90 claim, I consider within the spirit of my invention.

I claim:

The combination with an internal combustion engine having an intake manifold, of an auxiliary fuel reservoir located elevated relative to the said engine, a primer having a cup shaped member provided with 100 a removable cap, branches extending from said cap, one of the branches being connected with the reservoir; a needle valve arranged in another branch for controlling said branch connected with the reservoir, 105 the remaining branch forming an air intake, a delivery pipe leading from the said cup shaped member and having branches tapped into the intake manifold spaced from each other, and a foot operative means for 110 controlling the fluid in said delivery pipe.

In testimony whereof I affix my signature hereto.

EDWIN O. STEINBAUER.
